UNITED STATES PATENT OFFICE.

LEMUAL A. GREENE, OF GREENVILLE, SOUTH CAROLINA, ASSIGNOR, BY MESNE ASSIGNMENTS, TO FARMERS' COTTON GRADER COMPANY, A CORPORATION OF MAINE.

COTTON-GRADER.

9,52,802.

Specification of Letters Patent. Patented Mar. 22, 1910.

Application filed June 7, 1909. Serial No. 500,624.

To all whom it may concern:

Be it known that I, LEMUAL A. GREENE, a citizen of the United States, residing at Greenville, in the county of Greenville and 5 State of South Carolina, have invented certain new and useful Improvements in Cotton-Graders; and I do hereby declare the following to be a full, clear, and exact description of the invention, such as will enable others skilled in the art to which it 10 pertains to make and use the same.

My invention relates to cotton graders of the type shown and described in U. S. Patent No. 499,358, issued on June 13, 1893, 15 and No. 935,149 issued September 28, 1909, wherein a variety of samples of cotton of known quality are carried in a case under a transparent cover which may be extended beyond said case so that a sample of unknown quality may be placed below it and 20 compared with those in the case.

The case disclosed in the patents referred to is capable of conveniently carrying only a limited number of samples. If it is desired to have more samples, it would be necessary to lengthen the case which would tend 25 to make it inconvenient to handle.

The principal objects of my present invention are to provide for carrying a large 30 number of samples of determined grades; to make the device more compact; and to arrange the samples so that a quantity of cotton of unknown grade may simultaneously be compared with a large number of samples of predetermined grade.

The invention consists primarily of a case 35 containing a receptacle for receiving a sample of cotton of unknown grade, and a plurality of compartments arranged around 40 the receptacle.

The invention also consists of the generic and specific features of construction and arrangement of parts, substantially as hereinafter described and claimed.

45 In the accompanying drawing illustrating two embodiments of my invention, Figure 1 is a plan view of a cotton grader of rectangular form constructed in accordance with my invention; Fig. 2 is a central longitudinal section of the grader shown in Fig. 1, and, Figs. 3 and 4 are similar views of a circular form of grader.

In Figs. 1 and 2 of the drawing, 1 design-

nates a case which is made rectangular in 55 form and contains the compartments 2 arranged around an opening 3 which is preferably without a bottom. The compartments 2, each of which is intended to contain a sample of cotton of determined grade and of a grade different from that of the other 60 compartments, and the opening 3 are preferably though not necessarily covered by a transparent cover 4, which if desired may be of magnifying glass.

A transparent cover admits of samples in 65 the case being viewed without opening the compartments, and also protects said samples from dust or other foreign substances which would change their appearance if allowed to collect on them. Again, if it 70 is desired to seal the cases so that the samples contained therein cannot be removed or changed the transparent cover may be permanently attached to the casing for this 75 purpose.

The construction illustrated in Figs. 3 and 4 involves a circular case 1^a containing radial compartments 2^a arranged around a circular opening 3^a. The transparent cover 4^a if used, conforms to the shape of the case 80 and preferably extends over the opening 3^a as well as over the various compartments.

It is difficult to determine the grade of a sample of cotton when the sample is to be compared with cotton of various predetermined grades which is subject to different lights or conditions of light. Inasmuch as 85 by my device the cotton of known grades and the sample to be tested are compactly held, they are all in the same light and 90 therefore an accurate comparison is easily made.

The greater facility and convenience in 95 handling either of the forms of cotton grader shown and described herein as compared with either of those disclosed in the 100 patents referred to will be readily appreciated. The present forms are more compact and the transparent covers thereof when used do not project beyond their edges. An unknown sample may readily be placed in the opening in either of these new constructions where it is in close proximity to all of the samples of known quality, and with which it may be compared at a glance 105 and its grade instantly determined.

Having thus described my invention, what I claim as new, and desire to secure by Letters Patent, is:—

1. A cotton grader comprising a case having an opening therein, and a series of compartments for containing samples of cotton surrounding the opening.
2. A cotton grader comprising a case having an opening therein, and a series of compartments surrounding the opening, all of the compartments being arranged in close proximity to the opening.
3. A cotton grader comprising a case adapted to contain samples of cotton and having an opening arranged interiorly thereof, both the case and opening being covered by transparent material.
4. A cotton grader comprising a case having an opening therein, a series of compartments surrounding the opening, all the compartments being arranged in close proximity to the opening, both the case and opening being covered by transparent material.

partments being arranged in close proximity to the opening, both the case and opening being covered by transparent material.

5. A cotton grader comprising a case having a bottomless opening therein, and a series of compartments for containing samples of cotton surrounding the opening.

6. A cotton grader comprising a case having a bottomless opening therein, and a series of compartments for containing samples of cotton surrounding the opening, both the opening and the compartments being covered by transparent material.

In testimony whereof, I affix my signature, in presence of two witnesses.

LEMUAI A. GREENE.
